UNITED STATES PATENT OFFICE.

CHARLES R. PRATT, OF MONTCLAIR, NEW JERSEY.

CONTROLLING APPARATUS.

1,165,121.

Specification of Letters Patent. Patented Dec. 21, 1915.

Application filed August 29, 1914. Serial No. 859,258.

To all whom it may concern:

Be it known that I, CHARLES R. PRATT, a citizen of the United States, residing in Montclair, New Jersey, have invented certain Improvements in Controlling Apparatus, of which the following is a specification.

One object of my invention is to provide a relatively simple, compact and reliable combination of parts which while being particularly designed for the control and operation of the rudder of vessels of large size, shall be available for use for governing the operation of power actuated machines or apparatus such as intensifiers, elevators or the like.

A further object of the invention is to provide a novel controlling mechanism for hydraulic steering gear whose parts shall be so designed and associated that the speed of movement of the rudder shall be directly proportional to the power available for its movement, the arrangement of parts being such for example, that when a relatively great force opposes the movement of said member it is moved slowly and vice-versa either by a suitable motor or by hand;—in the case of a rudder its speed decreasing as it approaches a hard over position.

Another object of the invention is to provide a novel form of rudder operating mechanism whose parts shall be so designed and associated that the rudder may be operated at a relatively high speed without increasing the size of its operating plant, the invention also contemplating a novel form of follow-up or escapement mechanism with such an assembly of rudder control apparatus that there is no possibility of the various parts getting out of synchronism even after prolonged operation.

I also desire to provide a novel form of steering gear in which the parts are so coordinated that the speed of the rudder will vary with the sea pressure upon it and in which when arranged for hand steering the torque on the steering wheel is kept constant regardless of the sea pressure.

It is also desired to provide means whereby the operating torque on the steering wheel may be readily adjusted to suit the number of men available for its operation.

The invention also contemplates a novel means for maintaining the rudder in any adjusted position, without causing or tend-

ing to cause leakage of liquid from the hydraulic operating mechanism, the arrangement of parts being such that it is possible for said rudder to yield under abnormal conditions without breakage or unduly straining the mechanism associated therewith, after which it is automatically brought back to its original adjusted position.

These and other advantageous ends I secure as hereinafter set forth, reference being had to the accompanying drawings in which;

Figure 1 is a plan partly in section illustrating a controlling system designed and constructed according to my invention; Fig. 2 is a side elevation also partly in section, of certain of the apparatus shown in Fig. 1; Fig. 3 is a front elevation of the hydraulic rams and certain of their associated parts; Figs. 4 and 5 are elevations partly in section of two of the automatic controlling devices forming part of my invention; Figs. 6 and 7 are respectively a side elevation partly in section and an end elevation showing the detail arrangement of the mechanism for controlling the operation of the pump employed when the rudder is actuated by hand power; Fig. 8 is an elevation illustrating the connections between the pilot motor and its associated mechanism; Figs. 9 to 11 inclusive are elevations partly in section, illustrating modifications of certain features of my invention, and Fig. 12 is a fragmentary elevation showing a slight modification of one of the features of my invention.

In the above drawings, 1 represents the post of the rudder or other rotary or oscillatory structure which is to be moved and controlled, and this in addition to having other supporting structures (not shown) has a bearing 2 in a frame 3 made in the form of one or more suitably connected castings. To the head of the rudder post is connected a tiller which in the present instance consists of two parallel arms 4 properly keyed to said post and extending respectively above and below a plunger forging 5 whose ends in the form of rams are operative in two cylinders 6 and 7 rigidly clamped to the base or frame casting 3 so as to be in line with each other.

The two arms 4 are formed with radial guideways for blocks or cross-heads 8 mounted on trunnions 9 fixed to or forming part of the plunger forging 5 which, where

it enters the cylinders 6 and 7, is properly packed to prevent leakage of liquid. The lower trunnion is provided with a downwardly projecting extension 9^a operating in a guideway 3^a suitably carried on the frame 3. To one of the arms 4 is fixed a segmental rack 10 whose teeth mesh with the teeth of a gear 11, connected to a pulley 12, and with it loosely mounted upon a shaft 13 carried 10 in bearings 14 and 15 supported from the frame structure 3. This shaft has keyed or otherwise fixed to it one member 16 of a friction clutch whose second member 17 is attached to or formed as part of the pulley 12, and while this clutch may be of any desired or suitable form, I have shown the member 17 as a flat, disklike structure co-operating with a series of spring pressed plugs 18 of suitable dimensions and number 15 operative in cavities of the member 16. These plugs are at all times pressed toward the disk 17 by springs 19 so that under ordinary conditions the gear 11 is operatively connected to the shaft 13, although under 20 abnormal conditions, it is free to move independently thereon by reason of the turning of the disk relatively to the member 16. Also keyed to the shaft 13 is a worm wheel 20 engaged by a worm 21 fixed to a shaft 25 30 on which is also fixed a beveled gear 25. A worm wheel 23 is loosely mounted on a shaft 22 in line with the shaft 22^a and has fixed to it a beveled gear 24, there being a series of planetary gears 26 mounted on a 35 structure 26^a keyed to the shaft 22 and meshing with both beveled gears 24 and 25. For actuating or controlling the worm wheel 23 and the parts associated therewith, I provide a pilot motor 27 to whose armature shaft 28 is fixed a worm 28^a operatively engaging the worm wheel 23. The shaft 22 is made in two parts connected through a magnetic clutch 161 and while one part has fixed to it the gear carrying structure 26^a 40 the other part carries a gear 29 meshing with the teeth of a suitably guided rack 30. This is suitably connected at its upper end to one end of a lever 31, keyed or otherwise rigidly fixed to the stroke controlling shaft 50 32 of a variable stroke pump 33. The opposite end of the lever 31 is pivoted to a suitable form of centering device which in the present case I have shown as including a rod 33^a passing through a pair of plates 55 34 and 25 beyond the former of which it is provided with a head or stop nut 37, and between the two plates, concentric with said rod, is confined a spring 38. Also passing through both of the plates are two other rods 39, each of which has a head or nut 40 above the plates 34, and a second nut 41 below the plate 25. Each of said latter rods is connected to a supporting member 42 pivotally carried on any suitable fixed 60 65 bracket such as the structure indicated at

43, so as to permit of a slight rocking on the rods 39 and the parts connected thereto under the action of the lever 31.

In order to insure that the centering springs shall always return the shaft 32 to its no stroke position when the pilot motor stops, I mount the magnetic clutch 161 to separably connect the two parts of the shaft 22, and provide it with two independent windings. Of these the one indicated at 162 70 (Fig. 1) is in series with the armature of the motor 27, and current flows to it through suitable brushes *q*—*q* Fig. 4, and suitable slip rings or contacts (not shown). The winding 163 is connected across the line conductors by brushes *r*—*r*, Fig. 4, and suitable slip rings or contacts, though it is in series with a switch whose movable member 164 is attached to the lever 31 in such manner as to at all times engage a contact strip 165. Two other contact strips 166 and 167 are so placed that one or the other of them is connected to the strip 165 whenever the pump lever 31 moves a short distance to either side of its zero stroke position. 85 90

The driving shaft 56 of the pump 33 is operatively connected to a continuously operating motor 57 through differential gearing 58 which may be constructed as illustrated diagrammatically in Fig. 5. Said 95 gearing is shown as consisting of two beveled gears 59 and 60 respectively keyed to the shaft 56 of the pump and the armature shaft 61 of the motor 57. This latter shaft has loosely mounted on it a sleeve 62 100 having arms on which are rotatably mounted beveled pinions 63 each meshing with the two gear wheels 59 and 60. The arms or spindles 64 are journaled in bearings formed in a rotary casing 65 forming part of or attached to a frame 66 constituting a lever one of whose arms has pivoted to it a rod 67 105 operative on a centering spring 68. Said rod passes through a pair of plates 69 and 70 between which the spring 68 is confined by a pair of nuts 71 and 72 and there are also two supporting rods 73 passing through the two plates and rigidly connected to a cross bar 74 which is pivotally mounted on any suitable supporting structure (not 110 shown). Each of these rods 73 has a nut 75 above the plate 69 and a second nut 76 below the plate 70. The opposite end of the lever, 66 carries a suitably insulated contact arm 77 one portion of which is in constant engagement with a circularly curved contact strip 78, while a second portion is so formed to be capable of engaging any of a number of contacts 79 between which is connected armature resistance 80 of suitable material. 115 As shown in Fig. 5 the motor 27 has its field winding 81 permanently connected between two current supply mains *x* and *y* and has its armature normally connected directly to the latter of said current mains and to the 120 125 130

middle one of the contacts 79 with which the contact arm 77 of the lever 66 is normally held in engagement by the centering spring 68. Since this arm 77 is at all times in engagement with the contact strip 78, it will be noted that said armature is ordinarily connected directly across the current supply mains, since the main conductor α is permanently connected to the strip 78.

10 As shown in Fig. 1 the conductors 82 and 83 leading from the brushes of the motor 27 are respectively connected to a hand operated "follow-up" controller 84 placed on the bridge of a vessel or at any other desired point. This controller consists of an operating handle 85 carrying two contact plates or brushes 86 and 87 of which the first is designed to be capable of electrically connecting a contact ring 88 with any of the 20 number of contact strips 89, 90, 91 and 92 concentrically mounted upon a rotatably mounted plate 93 of insulating material. Between the segmental strip 91 and the relatively small contact plates 89 is connected 25 a body of armature resistance 94 and a second body of resistance 95 is likewise connected between the plates 90 and the segmental strip 92. Also mounted on the rotatable insulating plate 93 is a contact ring 96 capable of being connected with either of two segmental contact strips 97 and 98 by the contact 87 on the operating handle 85, it being noted that when this latter is in its middle or off position corresponding to the 35 amidships position of the rudder, these contacts 86 and 87 do not engage any of the contacts on the rotatable plate 93. This latter is operatively connected by a wire, chain, or equivalent device 99 with the pulley 12 which is rigidly fixed to and therefore necessarily rotatable with the gear 11 on the shaft 13, and the arrangement of parts is such as render impossible any slipping or 40 relative rotation of this pulley and the plate 93.

45 As shown in Fig. 1 the contact ring 96 is connected through a conductor 101 with the contacts 79, while the contact 97 is connected through a limit switch 102 and the conductor 82 with one of the armature terminals of the motor 27, this latter conductor being also connected to the segmental contact 92. Similarly the second armature terminal of the motor 27 is connected by the 50 conductor 83 to the segmental contact 91 and through a second limit switch 103 with the contact segment 98. The contact ring 88 is connected to the supply main γ and as before noted the contact strip 78 is connected 55 to the supply main α . The two cylinders 6 and 7 are connected through pipes 104 and 105 to the pump 33 which obviously is intended to be at all times rotated in the same direction by the motor 57, although the direction of the fluid flow delivered by it will

depend upon the direction of movement of the stroke varying shaft 32 and hence of the lever 31.

As so far described the steering gear has included only those parts required for operating the rudder by power, but if it should be desired that it shall be actuated by hand power, I provide a second pump 106 whose two openings are connected through pipes 107 and 108 to the cylinders 6 and 7 respectively. This pump as well as the pump 33 may be of any suitable construction having means whereby the stroke of its plungers and hence the amount of fluid delivered per revolution may be varied at will. As before, 70 the stroke varying shaft 109 has connected to it a lever 110 as shown in Fig. 6, and is normally held by means of a spring 111 operating on said lever in a position in which its plungers are adjusted for full stroke operation. In this case the spring is connected to said lever through a cap plate 112 which engages one end and its other end is connected to or supported by a second cap plate 113 which may be adjusted toward or from 85 the first cap plate by means of a hand wheel 114 having a nut operative to move a short rod 115 attached to the plate 113 either toward or from said spring. The outer extremity of the lever 110 is connected to a 90 three armed or bell crank lever 116 fulcrumed on any suitable support and having one of its arms connected through a link 117 to one end of a rotatable frame 118 whose opposite end is connected to a second arm of said lever 100 through a link 119, a bell crank lever 120 and a link 121. This frame is carried by a sleeve 122 rotatably mounted on the wheel shaft 123 to which is fixed the hand steering wheel 124. Said shaft has loosely 105 mounted on it a beveled gear 126 to which is fixed a spur gear 127, and has fixed to it a beveled gear 125. Beveled pinions 128 are rotatably carried on spindles connected to or formed as part of, the sleeve 122, and 110 their teeth mesh with both of the beveled gears 125 and 126. The spur gear 127 in turn meshes with the teeth of a gear 129 fixed to the driving shaft 130 of the pump 106.

115 Under conditions of operation and assuming that the rudder is to be operated by power, the electric motor 57 is run continuously, but obviously without causing the pump 33 to discharge any liquid, since the centering spring 38 normally holds the lever 31 in such position that the stroke adjusting shaft 32 maintains the pump plungers in their no stroke positions. Since there is practically no resistance to the rotation of the shaft 56, the differential casting 58 has practically no tendency to rotate. If now it be desired that the rudder shall be so actuated as to cause the vessel 120 to turn to starboard, the operating handle 125

85 is moved to bring its contact 86 into engagement with one of the contacts 90 and the contact ring 88, and also to cause its contact 87 to electrically connect the contact ring 96 and the segment 98. As a consequence current will flow from the supply main α to the contact strip 78 through the contact arm 77 to one of the contacts 79, and thence through contacts 96, 87, 98, limit switch 103, through the armature of the pilot motor 27, clutch winding 162, conductor 82, contact 92, resistance 95, contacts 90, 86 and 88, and thence to the current supply main γ . The motor 27 is thus started with all of the resistance 95 in circuit, and its revolution causes turning of the worm wheel 23, shaft 22 and beveled gear 24. Since the power necessary to move the rudder from its amidships position is necessarily far in excess of that of the relatively small motor 27, the worm wheel 21 is practically held stationary and as a result the rotation of the gear 29 through the worm 28, worm wheel 23, planetary gears 26 and clutch 161, causes longitudinal movement of the rack 30 and a turning of the lever 31 through a certain definite angle against the action of the spring 38. This movement of the lever likewise turns the shaft 32 and adjusts the plungers in the pump 33 so that liquid is delivered thereby through the pipe 104 to the cylinder 6 and is drawn in through the pipe 105 from the cylinder 7. The plunger 5 is thus moved longitudinally in the cylinders and through the trunnions 9 and blocks 8, the tiller arms 4 and with them the rudder post 1 are swung to starboard. Since the above turning of the stroke varying shaft 32 causes a transmission of power between the motor 57 and the pump 33, there is a relative turning of the differential casing 58 against the action of the centering spring 68, which results in more or less of the resistance 80 being cut into circuit with the armature of the motor 27, thereby slowing down said armature by decreasing its torque. Obviously before there can be any movement of the rudder as above noted under action of the pressure exerted upon the plunger 5, there must be revolution in a clockwise direction of the gear 11, and although this is securely locked from movement (except as hereafter noted) by the worm wheel 21, it is permitted to move by the action of the motor 27, which owing to the operation of the worm wheel 20 serves to drive the worm 21 as an escapement device. The torque of the pilot motor on its worm gear is applied to control lever 31, using the bevel gear attached to worm 21 as a fulcrum.

The various parts of the device are so designed that the maximum torque of the pilot motor (with no armature resistance in circuit) is just enough to fully compress the

centering spring 38 and put the pump at full stroke, which drives the segment 10 and the pinion 11 at maximum speed; the gear ratio being such that it synchronizes with the maximum speed of the pilot motor. Introducing enough resistance into the armature circuit of the pilot motor to give it torque enough to half compress the centering spring 38, puts the pump at half stroke and causes the gear 11 to be driven at half speed, thereby holding back the pilot motor to half speed, which is then its normal speed due to the amount of resistance introduced into its armature circuit. The pilot motor's normal speed is always enough greater than its gear ratio to the worm wheel 20, to cause the worm 21 to drive the worm wheel 20 with all the power delivered by the pilot motor and thereby relieve main motor 57 by a corresponding amount. This turning of the rudder and hence of the gear 11 turns the plate 93 of the controller 84 through the chain or wire 99 in such a direction that by the time the rudder has moved through the same angular distance as the angular displacement of the operating handle 85 from its amid position, said plate has been turned sufficiently to cause the various contact strips 98, 88 and 90 to disengage the contacts 87 and 86, thus open circuiting and stopping the motor 27. The rudder is now locked in this adjusted position independently of any holding action which may be exerted by the liquid in the cylinders 6 and 7, for the reason that any normal stress which may be exerted through the rudder post, rack 10 and worm wheel 20 on the worm 21, can not cause revolution of the same. There is therefore no leakage from the cylinders 6 and 7, although in the event of any abnormal strain brought to bear upon the rudder and its connecting mechanism, slipping would occur between the two members 16 and 17 of the friction clutch interposed between the gear 11 and the worm wheel 20. It is noted that when the above described movement of the lever 31 causes its contact 164 to complete the circuit of the shunt coil 163 of the magnetic clutch, the latter holds said lever in any position to which it may have been brought by the pilot motor, while this is operating. When said motor stops said lever is retained under the control of the rudder gears until the rams have nearly stopped moving, at which time the circuit of the shunt coil is opened by the lever contact 164, thus allowing the centering spring 38 to return the stroke controlling shaft 32 exactly to its zero stroke position. The load is thus taken off the motor 57 so that under the action of its centering spring 68, the gear casing or frame 66 is at once returned to its normal position, and the resistance 80 is again cut out of circuit with the motor 27. It will be noted that the centering spring 130

38 acting on lever 31, rack 30, pinion 29, shaft 22, and planetary gear 26, returns pump to zero stroke in the number of revolutions taken by worm 21, which always revolves in a direction opposite to that of the worm wheel driven by the pilot motor, the torque given to the worm 21 by the spring 38 being such as to cause it to drive the worm wheel 20. Therefore whether increasing or decreasing the stroke of the pump, the worm 21 always drives the worm wheel 20, otherwise, and should worm wheel 20 attempt to drive the worm 21, this worm gear would jam and stop on account of the angle of the thread of the worm 21, which has friction thrust washers instead of ball or roller thrust bearings. A further movement of the operating handle 85 to the left will again start the motor 27 and by the same sequence of operations as above described will cause the rudder to be moved still farther to starboard, it being possible to continue such movement until it reaches its hard-over position, when by means well known in the art, the limit switch 103 would be automatically opened, thus stopping the motor 27 and leaving the rudder locked in said position. A movement of the operating handle in the opposite direction to that above noted will likewise cause the same series of operations as above described, except that in this case the direction of rotation of the motor 27 will be reversed, while the controlling shaft 32 of the pump 33 will be so turned that the plungers of the pump are caused to discharge liquid through the pipe 105 to the cylinder 7 and draw it from the cylinder 6 through the pipe 104. In such case the motor 27 rotates the worm 21 in such a direction as to permit rotation of the gear 11 in a counter-clockwise direction and a movement of the rudder to port, under action of the fluid under pressure in the cylinder 7. As before, the movement of the rudder will cause the plate 93 of the controller 84 to follow up the operating handle 85 so as to open circuit the pilot motor 27 and lock the rudder from further movement, when the latter has moved into the angular position occupied by the said handle 85.

If it be desired to operate the rudder by hand power, the centering spring 111 is adjusted by means of its hand wheel 114 to a predetermined tension dependent upon the number of men available for operating the steering wheel 124, and if two men are to operate said wheel, power is at first transmitted through the gears 127 and 129 to the driving shaft 130 of the pump 106. Since the controlling shaft 109 of this pump is normally maintained by the spring 111 with the pump plungers in their full stroke positions, said pump delivers liquid at its maximum rate of flow through the pipe 108 to the cylinders 7 for example, and draws

liquid from the cylinder 6 through the pipe 107, thus causing longitudinal movement of the rams 5 toward the right. The rudder is thus turned to port; for the first part of this movement it swings at a relatively high speed, since the opposing resistance is comparatively slight. As this resistance and hence the load on the pump 106 increases by reason of the further departure of the rudder from its amidships position, the beveled pinions 128 with the sleeve 122 are caused to turn on the wheel shaft 123 thereby so moving the lever 110 against action of the spring 111 as to reduce the stroke of the pump plungers. The amount of liquid delivered by one revolution of the wheel 124 is thereby reduced and while the power applied to the movement of the rudder remains the same, its speed of movement is correspondingly cut down. In spite of the fact therefore, that as the rudder approaches its hard over position, the work necessary to move it is not increased, it is still possible for the men operating the wheel to perform this work, since the speed of movement of the rudder continues to decrease by the gradual reduction of the length of stroke of the pump plungers. It will be noted that this operation corresponds with that occurring when the rudder is actuated by power. Obviously as soon as movement of the hand wheel ceases the stroke controlling shaft 109 of the pump 106 is automatically returned to its full stroke position by the spring 111 and when the wheel is turned in the opposite direction the sea pressure on the rudder assists in its return to the amidships position in a minimum of time, since the pump plungers operate at full stroke in view of the relative ease of movement of the driving shaft 130 while the liquid is being permitted to flow from the cylinder 6 through the pump to the cylinder 7. Obviously when the hand steering gear is employed, the nut 140 on the shaft 13 may be slackened off, thus permitting movement of the gear 11 and its connected parts independently of the pilot motor and the pump 33. The valves 141 and 142 in the pipes 104 and 105 would likewise be closed and valves 143 and 144 in the pipes 107 and 108 opened.

In the case of the power driving mechanism it will be understood that the adjustment of the stroke of the pump 33 is dependent not only upon the operation of the pilot motor 27 but also upon the pressure of the sea upon the rudder, for the movement of this shaft is dependent upon the resultant of the forces originating from these sources. If the rudder is in the amidships position, for example, the sea pressure is zero and if the pilot motor 27 is started by operation of the lever 85, the constantly operating pump 33 as previously described, is at once adjusted so that its plungers will operate at

the full stroke. If, on the other hand, the rudder be in some position other than amidships, the operation of the pilot motor which would permit said rudder to approach the 5 amidships position has little or no effect upon the stroke varying shaft 32 of the pump 33, since the sea pressure on the rudder permits easy revolution of the worm 21 by the pilot motor, and the bringing of the 10 rudder to the amidships position largely by the sea pressure. When the rudder has passed beyond the amidships position, the sea pressure again acts as a retarding force and since said rudder and hence the worm 15 wheel 20 must be positively driven, the pilot motor at once acts through the lever 31 upon the stroke adjusting shaft of the pump 33 to cause it to deliver fluid under pressure to the cylinders 6 and 7. Considering the motor 57 20 therefore as the source of power from which the rudder is primarily operated, it will be noted from the foregoing description that I have provided means whereby the sea pressure on the rudder is caused to determine the 25 amount of power delivered from said source. While the work done is substantially constant, the speed of movement of the rudder gradually decreases as it is moved from the amidships to the hard over positions. When 30 the rudder is moving toward the amidships position the work required is a minimum while its speed of movement is a maximum. If desired I may replace the differential mechanism, shown in Fig. 1 as connected between the motor 57 and the pump 33, by a hydraulically actuated device such as is illustrated in Fig. 9. This consists of a pair of cylinders 170 and 171, connected by pipes 172 and 173 respectively to the cylinders 6 40 and 7. Two plungers 174 and 175 respectively operate in said cylinders 170 and 171 and are both connected by a link 146 to a lever 147, fulcrumed to a suitable supporting structure and carrying a contact member 77^a, which like member 77 (Fig. 5) 45 contacts with the contacts 79 and 78 as heretofore described. A spring 148 normally holds the lever 147 in such position that all of the resistance 80 is cut out of the armature circuit 50 of the motor 27, but whenever there is fluid under pressure in either of the cylinders 6 or 7, it acts through the pipes 172 and 173 to move either one or the other of the plungers thus causing the lever and its contact member 77^a to take up a corresponding position 55 against the action of the spring 148. As the pressure in the cylinders 6 or 7 rises there is thus introduced into the circuit of the armature of the motor 27, more or less of the resistance 80, so that the speed of said motor is 60 cut down and its torque is decreased as the rudder is moved from its amidships position, as previously described. Similarly, the differential mechanism shown in Fig. 1 as connected between the hand wheel 124 and the

pump 106 may be replaced by either of the devices shown in Figs. 10 or 11, which include a lever 150 connected to the stroke regulating and reversing shaft 109 of the pump, together with a centering spring 111^a which tends to maintain said shaft in its full stroke position. This spring is operative on one arm of the lever whose other arm is connected through a link 151 to a pair of plungers respectively operative in two cylinders 75 152 and 153 which, like the cylinders 140 and 141 are connected through pipes 154 and 155 to the two cylinders 6 and 7 respectively. As before any rise of pressure in the ram cylinders causes movement of the plungers 80 out of their cylinders 152 or 153 and the resulting movement of the lever 150 with the partial rotation of the shaft 109 will shorten the stroke of the pump plungers to a degree corresponding to the pressure, which pressure in any case is dependent on the sea pressure on the rudder. 85

In the case of Fig. 11, I have provided a single cylinder 156 having a single plunger 157 operatively connected through a link 90 151^a to the lever 150 and this cylinder is connected through the pipe 158 to a valve cylinder 159 containing a cylindrical valve 160. In this case the two pipes 154 and 155 are connected respectively to the opposite ends 95 of the valve cylinder, so that fluid under pressure delivered from one of them moves the valve 160 into such a position that free communication is established between said pipe and the cylinder 156 with the results 100 noted in connection with Fig. 10, and similarly, fluid delivered from the other pipe likewise moves the valve to permit flow of said fluid to the said cylinder. The pilot motor requires no break to stop or hold it, as 105 the centering spring 38 always applies a measured torque load to stop and hold the worm on the armature shaft of the pilot motor. With the pilot motor stopped and the pump at zero stroke, the worm wheel 20 110 is locked by its worm 21 which would either have to drive the worm of the pilot motor through its worm wheel or would compress the centering spring 38. The worm wheel 20 is therefore locked to resist any torque 115 applied to it by sea pressure on the rudder through the segment 10, pinion 11 and the friction clutch. By the use of the centering spring 38, the magnetic clutch 161 and its associated apparatus, I insure that the lever 120 31 shall be certainly returned to its exact zero position when the pilot motor stops, and while the stroke of the pump 33 is always under control of said motor the lever is automatically released from the control 125 of the rudder gears when the pump stroke has been reduced to any predetermined small amount. If desired the clutch 161 may have its shunt winding omitted, in which case the pump 33 is brought to zero stroke in consid- 130

erably less time than would be required to increase such stroke by the same amount, the centering spring 38 being free to return the lever 31 to its zero stroke position as soon as the pilot motor circuit is opened without waiting for said motor to stop. There is thus a perfect response to the steering wheel (or lever) and the follow up wheel will stop the instant it reaches its off position. While the acceleration of the rudder will not be affected by this clutch releasing apparatus, the stopping time can be reduced to a fraction of a second without causing undue strain to any part. This is advantageous in case my invention should be employed for training a gun turret instead of actuating a rudder and would be available regardless of whether the control system was of the follow up or of non follow up type. In some cases spur gearing 170 and 171 Fig. 12 may be substituted for the worm gearing in connecting the pilot motor 27 to the gear 24, in which case the centering spring 38 is free to rotate the armature of said motor as soon as its circuit is opened, and thus bring the pump 33 to exact zero stroke. This action, however, is slower than that of the magnetic clutch by the amount of time required for the pressure of the centering spring to stop and reverse the direction of movement of the pilot motor.

I claim;—

1. The combination of a rudder; a source of power for operating said rudder; and means controlled by the sea pressure on the rudder for varying the force impressed thereon in proportion to its resistance to turning.

2. The combination of a rudder; a source of power for operating said rudder; means controlled by the sea pressure on the rudder for varying the force impressed thereon in proportion to its resistance to turning; and means for adjusting said force at will.

3. The combination of a rudder; operating means therefor including a variable stroke pump; and means controlled by the sea pressure on the rudder for varying the stroke of the pump.

4. The combination of a rudder; operating means therefor including a variable stroke pump and a motor for continuously operating the same; and means controlled by the sea pressure on the rudder for varying the stroke of the pump.

5. The combination of a rudder; operating means therefor including a variable stroke pump; a pilot motor; and means controlled jointly by said pilot motor and by the sea pressure on the rudder for automatically varying the stroke of said pump.

6. The combination of a rudder; operating means therefor including a variable stroke pump; with means for automatically adjusting the stroke of the pump in accord-

ance with the position and direction of movement of the rudder.

7. The combination of a rudder; operating means therefor including a continuously operating variable stroke pump; a pilot motor; means for manually controlling said pilot motor; and means controlled by the sea pressure on the rudder and co-operating with the pilot motor for automatically varying the stroke of the pump.

8. The combination of a rudder; operating means therefor; a pilot motor for controlling said operating means; and a device for governing the pilot motor.

9. The combination of a rudder; operating means therefor; a pilot motor for controlling said operating means; a controller for said motor; and floating gear connecting the rudder and said controller.

10. The combination of a rudder; operating means therefor; a pilot motor for controlling said operating means; a follow-up controller for governing the pilot motor; and floating gear connecting the rudder with a movable element on said controller.

11. The combination of a rudder; operating means therefor; and a device independent of said means for automatically locking the rudder in any given position, with controlling apparatus for the operating means connected to automatically release the locking device.

12. The combination of a member to be operated; operating means therefor; and a device independent of said means for automatically locking the member to be operated in any given position, with controlling apparatus for the operating means connected to automatically release the locking device.

13. The combination of a rudder; operating means therefor; and an escapement device for following-up said operating means.

14. The combination of a rudder; operating means therefor; and locking means for said operating means constructed to operate as an escapement device for following-up the operating means.

15. The combination of a rudder; operating means therefor including cylinders and plungers; a continuously operating variable stroke pump connected to the cylinders; and a pilot motor for adjusting the stroke of said pump at will.

16. The combination of a rudder; operating means therefor; an escapement device for said means; and a pilot motor connected to actuate the escapement device and control the operating means.

17. The combination of a member to be operated; operating means therefor; an escapement device for said means; and a pilot motor connected to actuate the escapement device and control the operating means.

18. The combination of a rudder; means

- including cylinders and plungers for operating said rudder; with a device independent of said parts for automatically locking the rudder in any given position, and controlling apparatus for the operating means connected to automatically release the locking means.
19. The combination of a rudder; operating means therefor; means for locking the rudder in any given position; and a device connected between the rudder and said means and capable of yielding under abnormal stress.
20. The combination of a rudder; operating means therefor; means for automatically locking the rudder in any given position; and a friction clutch adjusted to slip under abnormal stress upon the rudder, connected between said rudder and said locking means.
21. The combination of a rudder; operating means therefor; worm gearing operatively connected to the rudder; and a pilot motor operatively connected to said gearing.
22. The combination of a rudder; operating means therefor including a variable stroke pump; worm gearing operatively connected to the rudder; a pilot motor operatively connected to said gearing; and means for causing the operation of the pilot motor to vary the stroke of the pump.
23. The combination of a member to be operated; operating means therefor including a variable stroke pump; worm gearing operatively connected to the member to be operated; a pilot motor operatively connected to said gearing; and means for causing operating of the pilot motor to vary the stroke of the pump.
24. The combination of a rudder; operating means therefor including a variable stroke pump; worm gearing operatively connected to the rudder; a member for varying the stroke of the pump; and a differential gear connecting said member, the pilot motor and the worm gearing.
25. The combination of a member to be operated; operating means therefor including a variable stroke pump; worm gearing operatively connected to the member to be operated; a member for varying the stroke of the pump; and a differential gear connecting said member, the pilot motor and the worm gearing.
26. The combination of a rudder; operating means therefor including a variable stroke pump; a member for varying the stroke of said pump; a pilot motor; and means including a differential gear connecting the pilot motor, said stroke varying member and the rudder.
27. The combination of a rudder; operating means for the rudder including cylinders and plungers; a continuously operative variable stroke pump connected to the cylinders; a toothed segment connected to the rudder; worm gearing; means including a friction clutch connecting said gearing with said segment; a member for varying the stroke of the pump; a pilot motor; and a differential gear connecting said member, the pilot motor and the worm gearing.
28. The combination of a rudder; operating means therefor including a pump; a motor for driving said pump; a pilot motor for controlling the pump; and a device dependent upon the load on the pump for controlling the operation of said pilot motor.
29. The combination of a rudder; operating means therefor including a pump; a member for driving said pump; a pilot motor for controlling the pump; and means connected between the pump and its driving motor for automatically governing the operation of the pilot motor.
30. The combination of a rudder; operating means therefor including a pump; a motor for driving said pump; a pilot motor for controlling the pump; and a device dependent upon the load on the pump for varying the torque of the pilot motor.
31. The combination of a member to be operated; operating means therefor including a pump; a motor for driving said pump; a pilot motor for controlling the pump; and a device dependent upon the load on the pump for varying the torque of the pilot motor.
32. The combination of a rudder; means for operating said rudder including a pump; a driving motor for the pump; a pilot motor for controlling the pump; and mechanism connected between the pump and its driving motor for varying the current flow in the pilot motor.
33. The combination of a rudder; operating means therefor including a pump; a driving motor for the pump; means including a differential gear for connecting said pump and its motor; a pilot motor for controlling the pump; and a device actuated by said differential gear for varying the current flow in the pilot motor.
34. The combination of a rudder; means for operating the same including a variable stroke pump; a motor for varying the stroke of the pump; and means including a differential gear for governing said motor.
35. The combination of a member to be operated; actuating means therefor; a pilot motor controlling said means; and means dependent on the torque of the pilot motor for governing the actuating means.
36. The combination of a member to be operated; actuating means therefor; a pilot motor controlling said means; means dependent on the torque of the pilot motor for governing the actuating means; and means for varying the torque of the pilot motor.
37. The combination of a member to be operated; actuating means therefor; a pilot motor controlling said means; means dependent on the torque of the pilot motor for governing the actuating means; and means for varying the torque of the pilot motor.

operated; actuating means therefor; a pilot motor for controlling said means; and apparatus including differential gearing for controlling the actuating means and said 5 member.

38. The combination of a variable stroke pump; a motor driven therefrom; means operatively connected to the motor and including a pilot motor for controlling the 10 pump; with a device for automatically bringing the pump to exact zero stroke when the pilot motor ceases operation.

39. The combination of a pump; means for varying the stroke thereof; a device 15 tending to bring the stroke varying means to its zero position; means including a pilot motor for actuating the stroke varying means to increase the stroke of the pump; with a device for insuring the return of the 20 stroke varying means to an exact zero position after it has been moved therefrom.

40. The combination of a variable stroke pump; a motor actuated by fluid from the 25 pump; a pilot motor; stroke varying means for the pump; connections between the fluid motor, the pilot motor and the stroke varying means; a device tending to center the stroke varying means; and means for automatically disconnecting the fluid motor 30 from the stroke varying means under predetermined conditions.

41. The combination of a variable stroke pump; a motor actuated by fluid from the

pump; a pilot motor; stroke varying means for the pump; connections between the fluid 35 motor, the pilot motor and the stroke varying means; a spring for centering the stroke varying means; and means for permitting action of the spring when the pilot motor ceases operation.

42. The combination of a variable stroke pump; a motor actuated by fluid from the 40 pump; a pilot motor; stroke varying means for the pump; connections between the fluid motor, the pilot motor and the stroke varying 45 means; means for centering the stroke varying means; and a clutch included in the connections between the pilot motor and the stroke varying means.

43. The combination of a variable stroke 50 pump; a motor actuated by fluid from the pump; a pilot motor; a stroke varying device for the pump; connections between the fluid motor, the pilot motor and the stroke varying means; means for centering the 55 stroke varying means; with a magnetic clutch in circuit with the pilot motor and connected between the fluid motor and the stroke varying means.

In testimony whereof, I have signed my 60 name to this specification, in the presence of two subscribing witnesses.

CHARLES R. PRATT.
